UNITED STATES PATENT OFFICE.

VICTOR E. KENT, OF JOHNSON CITY, TENNESSEE, ASSIGNEE OF ONE-THIRD TO JAMES A. MARTIN AND ONE-THIRD TO RICHARD F. BREWER, BOTH OF JOHNSON CITY, TENNESSEE.

CATTLE-GUARD.

1,102,056.

Specification of Letters Patent. Patented June 30, 1914.

Application filed May 28, 1912. Serial No. 700,263.

To all whom it may concern:

Be it known that I, VICTOR E. KENT, a citizen of the United States, residing at Johnson City, in the county of Washington and State of Tennessee, have invented certain new and useful Improvements in Cattle-Guards, of which the following is a specification.

This invention relates to cattle guards and is designed more particularly as an improvement on the cattle guard disclosed in my co-pending application filed January 9, 1912, Serial No. 670,334.

The guard disclosed in the said application embodies fixed guard members which are suspended for swinging movement and it is one aim of the present invention to simplify and improve the construction of the fixed guard sections and provide an improved means for suspending the movable sections.

For a full understanding of the invention reference is to be had to the following description and accompanying drawing, in which:

Fig. 1 is a top plan view of one form of the improved guard. Fig. 2 is a vertical sectional view therethrough. Fig. 3 is a vertical transverse section on the line 3—3 of Fig. 2. Fig. 4 is a detail view in elevation of a portion of one of the fixed guard sections. Fig. 5 is a view similar to Fig. 2 illustrating a slight modification of the invention.

Corresponding and like parts are referred to in the following description and indicated in all the views of the accompanying drawing by the same reference characters.

In the drawings, the rails are indicated by the numeral 1 and the ties upon which they are mounted by the numeral 2.

As before stated, the invention contemplates the provision of fixed and movable guard sections, and in that form of the invention shown in the first four figures of the drawings each of the fixed sections consists of a pair of plates, each indicated by the numeral 3 and these plates are of greater or less length, depending upon whether they are to extend between the rails 1 or are to be located outwardly of the said rails, as clearly shown in Fig. 1 of the drawings. As illustrated in Fig. 2 of the drawings, the upper edges of the ties 2 are cut away as at 4 between and beyond the rails 1 and

the plates 3 comprising each guard section are disposed against the cut away surfaces 4 in the relation shown in the said section 2 and are secured in place by means of spikes 5 driven therethrough and into the said ties. 60 Each of the plates is formed at its upper edge with an upstanding flange 6 and these flanges abut against each other as shown in the drawing and at intervals are secured by means of rivets or other suitable fastening devices 7. Each of the flanges 6 is toothed as indicated at 8 and the teeth of the two flanges of each fixed guard are alternated so that a continuous saw-tooth edge is presented at the ridge of the section as illustrated at the ridge of the section as illus- 70 trated in Fig. 3.

In the form of the invention shown in the first four figures of the drawings, each movable guard section of the device includes a tread-plate 9 which is of metal and has 75 its forward and rear edges flanged as at 10 and this plate is provided with a number of upstanding spikes or spurs 11 which are arranged relatively close together, as shown in Fig. 1 of the drawings, it being understood that these spikes or spurs extend throughout the entire area of the upper surface of the plate. These plates 9 are suspended between the ties 2 from bars which extend parallel to the rails and outwardly 85 of the same. Each of these bars is indicated at 12 and the flanges 6 of each fixed guard section are formed with registering notches 13 in which the bars 12 are engaged. 90

It will be understood by referring to Figs. 1 and 2 of the drawings that each bar has its end portions bent to extend downwardly as at 14 and twisted to form flat terminal portions 15 which are disposed against the upper face of one of the plates 3 of each 95 endmost fixed guard section, and these terminal portions of the bars are secured by spikes 5 as shown in Fig. 2 of the drawings. In suspending the plates 9 from the bars 12, a pair of clevises 16 are pivotally supported 100 as at 17 between each two of the ties 2 and a link 18 is connected to each clevis 16 and by means of a link 19 to an eye 20 secured upon the upper side of the plate 9. This arrangement is clearly shown in Figs. 2 and 105 3 of the drawings and it will be understood that the tread-plates 9 are free to swing forwardly and rearwardly and also laterally.

It will be observed from inspection of Figs. 2 and 3 that the plates 9 are sup- 110

ported in a horizontal plane substantially co-incident with the lower edges of the adjacent ones of the plates 3 of the fixed guard sections and that the flange 2 and rear edges 5 of the said plates 9 are located adjacent to the lower edges of the plates 3.

In the form of the invention shown in Fig. 5 of the drawings, triangular blocks 21 are substituted for the plates 3 comprising 10 the fixed guard sections of the device and spikes 22 are driven through the pieces of blocks and project at their upper ends above the apex or ridge of each block and serve the same purpose as do the toothed flanges 15 6 of the said plates 3. Each block 21 in this form of the invention is formed with a notch 23 corresponding to the notches 13, previously described, and receiving the supporting bar 24 for the movable or suspended 20 guard-sections. The ends of the bar 24 in this form of the invention are bent and secured in the same manner as previously described.

In this form of the invention the movable 25 or suspended guard-section consists of two boards, one of which is indicated by the numeral 25 and the other by the numeral 26, and pins 27 are driven through the board 26 and the board 25 is disposed against the under side of the board 26 and the eye-members 30 of the suspension which corresponds to the eye 20, heretofore described, are provided with shanks 28 which are secured through the two boards and hold them in 35 assembled relation in the manner shown in Fig. 5.

Having thus described the invention what is claimed as new is:—

1. In a cattle guard, spaced guard sections, each including a body having oppositely inclined surfaces the bodies of the sections at their ridges being formed with notches, and a bar extending through the notches and secured at its ends to the outer 45 sides of the endmost sections.

2. In a cattle guard, spaced guard sections, each including a body having oppositely inclined surfaces, the bodies of the sections at their ridges being formed with 50 notches, a bar extending through the notches and secured at its ends to the endmost sections, and other guard sections suspended for swinging movement from the said bar between the first mentioned guard sections.

3. In a cattle guard, spaced guard sections, each including plates arranged in oppositely inclined relation and provided at their upper edges with upstanding flanges, each of the flanges being formed at intervals with teeth extending less than the entire height of the flange, the plates being arranged with the teeth of the flanges alternating, means securing the flanges together, the flanges of the plates of each section being formed with notches, a bar seated within 65 the notches, and a swinging guard section supported from the bar and extending between the first mentioned guard sections.

4. In a cattle guard, spaced guard sections, each including plates arranged in oppositely inclined relation and provided at their upper edges with an upstanding flange, each of the flanges being formed at intervals with teeth extending less than the height of the flange, the plates being arranged with 70 their flanges abutting and with the teeth of the flanges alternating, securing elements fitted through the flanges, the flanges of the plates of each section being formed with registering notches, the said notches extending the entire height of the flanges, a bar fitted within the notches, the bar having a down-turned end extending beside the upper face of one of the inclined plates and provided with an opening, the plate being 80 provided with an opening with which the opening in the down-turned end of the bar is in registration, a securing element fitted through the said opening and designed to be driven into a tie straddled by the plates, 85 and a movable guard section supported by the said bar between the first mentioned guard sections.

5. In a cattle guard, spaced guard sections, said sections having oppositely inclined surfaces and each section being provided at its ridge with a notch, a bar removably disposed edgewise within the notches, means securing the ends of the bar to the end ones of the guard sections, and a 95 movable guard section suspended from the bar between a pair of fixed guard sections.

In testimony whereof I affix my signature in presence of two witnesses.

VICTOR E. KENT. [L. S.]
